(57) **CLAIM**

The ornamental design for a white coat garment as shown and described.

DESCRIPTION

FIG. 1 is a perspective view of a white coat garment showing my new design;

FIG. 2 is a front elevational view thereof;

FIG. 3 is a front elevational view of the white coat garment in an open configuration;

FIG. 4 is a top plan view of the white coat garment in a closed configuration;

FIG. 5 is a bottom plan view thereof;

FIG. 6 is a right elevational view thereof;

FIG. 7 is a left side elevational view thereof; and,

FIG. 8 is a rear elevational view thereof showing my design. The cross-hatched lines in the drawings show shading that defines the contours of the white coat garment and do not reflect a particular surface ornamentation or material.
